(57) **CLAIM**

The ornamental design for a gas cylinder safety guard, as shown and described.

DESCRIPTION

FIG. 1 is a perspective view of a gas cylinder safety guard of the present invention;

FIG. 2 is a front view of a gas cylinder safety guard of FIG. 1;

FIG. 3 is a rear view of a gas cylinder safety guard of FIG. 1;

FIG. 4 is a left lateral view of a gas cylinder safety guard of FIG. 1;

FIG. 5 is a right lateral view of a gas cylinder safety guard of FIG. 1;

FIG. 6 is a top view of a gas cylinder safety guard of FIG. 1; and,

FIG. 7 is a bottom view of a gas cylinder safety guard of FIG. 1.
